CASSEROLE OR SIMILAR ARTICLE

Frank J. Benes, Lancaster, Ohio, assignor to Anchor Hocking Glass Corporation, Lancaster, Ohio, a corporation of Delaware

Filed Dec. 6, 1966, Ser. No. 4,928

Term of patent 14 years

(Cl. D44—15)

FIG. 1 is a perspective view of a casserole or similar article showing my new design;

FIG. 2 is an exploded perspective view thereof;

FIG. 3 is a top view thereof;

FIG. 4 is a side view thereof;

FIG. 5 is a sectional view taken along line 5—5 of FIG. 3; and

FIG. 6 is a sectional view taken along line 6—6 of FIG. 4.

The characteristic feature of the design resides in the combination of downwardly curved handles with a casserole body, the upper portion of which is slightly tapered and the lower portion of which has a greater taper, and a shallow cover member having a knob of the configuration shown.

I claim:

The ornamental design for a casserole or similar article, substantially as shown and described
